[57] CLAIM

The ornamental design for an automatic original feeder for copying machine, as shown and described.

DESCRIPTION

FIG. 1 is a top and right front perspective view of an automatic original feeder for copying machine showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a sectional elevational view thereof taken along line A—A of FIG. 2;

FIG. 8 is a sectional elevational view thereof taken along line 8—8 of FIG. 2;

FIG. 9 is a bottom plan view thereof; and

FIG. 10 is a top and right-front perspective view thereof, the broken-line showing of a copier being environmental only and forming no part of the claimed design.
